(57) **CLAIM**

The ornamental design for an umbrella frame, as shown and described.

DESCRIPTION

FIG. 1 is a perspective view of an umbrella frame showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a perspective view of a single umbrella rib of the umbrella frame, shown separately for ease of disclosure.
The broken lines depict portions of the article that form no part of the claimed design.
